UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,590, dated August 28, 1894.

Application filed July 31, 1894. Serial No. 519,096. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of flambeau or torch-like ornaments tied with a bow of 10 ribbons and connected by festoons of flowers and leaves as represented in the accompanying drawing. The ornaments are placed at uniform distances apart over the surface of the paper. The border or upper portion of the 15 design is formed of similar flambeau or torch-

like ornaments tied with bows of ribbons and connected by festoons of flowers and leaves and ribbons as shown in the drawing.

What I claim is—

1. The design for wall paper herein shown 20 and described.

2. In the design for wall paper the border herein shown and described.

Witness my hand this 28th day of July, 1894.

CHARLES BOOZE.
